US0D1102469S

(12) **United States Design Patent** (10) **Patent No.:** **US D1,102,469 S**
Coffman et al. (45) **Date of Patent:** **** Nov. 18, 2025**

(54) **DISPLAY SCREEN OR PORTION THEREOF WITH GRAPHICAL USER INTERFACE**(71) Applicant: **Apple Inc.**, Cupertino, CA (US)(72) Inventors: **Patrick Lee Coffman**, San Francisco, CA (US); **Stephen O. Lemay**, Palo Alto, CA (US); **Christopher Daryl Soli**, Mountain View, CA (US)(73) Assignee: **Apple Inc.**, Cupertino, CA (US)(**) Term: **15 Years**(21) Appl. No.: **29/890,005**(22) Filed: **Apr. 19, 2023****Related U.S. Application Data**

(63) Continuation of application No. 29/801,903, filed on Aug. 2, 2021, now Pat. No. Des. 988,341, which is a continuation of application No. 29/692,707, filed on May 28, 2019, now Pat. No. Des. 926,781.

Primary Examiner — Daniel J Domino(74) *Attorney, Agent, or Firm* — Saidman DesignLaw Group, LLC(57) **CLAIM**

The ornamental design for a display screen or portion thereof with graphical user interface as shown and described.

DESCRIPTION

The sole FIGURE is a front view of a display screen or portion thereof with graphical user interface showing the claimed design.

The peripheral dashed broken lines depict a display screen or portion thereof, and form no part of the claimed design. The interior broken lines depict portions of the graphical user interface which form no part of the claimed design.
